AUTOMATIC CONTROL FOR REVERSE-LOCK MECHANISMS

Application filed May 29, 1924. Serial No. 716,600.

The present invention is an improved automatic control for reverse lock mechanisms, such as is disclosed in Letters Patent of the United States Number 1,362,783 issued to Charles P. Cirac, on December 21, 1920.

This invention contemplates means, associated with an automobile transmission and responsive to any conventional type of gear shift mechanism, for automatically rendering operative or inoperative a mechanism designed to prevent reverse movement of said automobile. The value of such a lock for preventing backward movement of an automobile, independent of failure of brakes or engine or a faulty operation of either, is obvious and well recognized.

The principal object of this invention is to provide means, responsive to certain gear changes, whereby said lock will be of service upon demand and will be instantly thrown out of engagement when no longer required. Other objects and advantages will appear as this description proceeds.

In this specification and the annexed drawings, the invention is illustrated in the form considered to be the best, but it is to be understood that the invention is not limited to such form because it may be embodied in other forms, and it is also to be understood that in and by the claims following the description it is desired to cover the invention in whatever form it may be embodied.

In the accompanying three sheets of drawings, Figure 1 is a cross sectional view of a propeller shaft showing in elevation thereon a reverse lock and my control as the same would appear from the rear,

Figure 2 is a side elevation of Fig. 1,

Figure 3 is an elevation reverse to Figure 1 and shows means for connection with an automobile transmission housing,

Figure 4 is a fragmentary top plan view of Figure 3 showing certain parts thereof as viewed from above,

Figure 5 is an exploded view of Figure 2, showing the component parts in side elevation in the positions they would assume if successively withdrawn,

Figure 6 is a fragmentary top plan view, similar to Figure 4, showing the parts in the

positions they would assume while the vehicle is reversing,

Figure 7 is a perspective view illustrating members of my automatic control, parts being separated for the purpose of better illustration,

Figure 8 is a fragmentary view in elevation of a stationary member secured to the transmission housing and containing dogs, (this view is taken in the direction of the arrow VIII, of Figure 5.)

Figure 9 is an elevation of a control plate, and the view is taken in the direction indicated by the arrow IX, Figure 5,

Figure 10 is an elevation of a housing member and is taken in the direction indicated by the arrow X, Figure 5,

Figure 11 is a fragmentary top plan view of Figure 10,

Figure 12 is a cross section, taken on line XII—XII of Figure 8,

Figure 13 is a section of a pair of slide members, the section line being indicated by the line XIII—XIII of Figure 4,

Figure 14 is an elevation of a ratchet plate, the view being taken as indicated by the arrow XIV, Figure 5,

Figure 15 is a diagrammatic view showing my control and a foot pedal for coaction therewith in a forward position,

Figure 16 is a view of a portion of Figure 15 as the parts would appear in a reversing position,

Figure 17 is a perspective view of a sliding latch member,

Figure 18 is a side elevation of a selector rod, the view being projected from Figure 15,

Figure 19 is a side elevation of a selector rod, the view being projected from Figure 15,

Figure 20 is a plan view of a slide member.

Referring to the drawings, Figures 1 and 2, the numeral 1 indicates a driven shaft, such as an automobile propeller shaft, which is to be provided with a lock preventing reverse rotation and means controlling said lock. At 2 I show a circular disc member provided with a continuous flange 3, adapted to register with an opening in an automobile transmission housing and be secured thereto as by bolts through holes 4, the object being to secure

said disc in stationary relation to said transmission. The disc 2 is provided with a plurality of recesses 6, Figure 8, here shown as being quadrilaterally disposed in that face of said disc which is remote from the transmission. The purpose of these recesses is to receive dogs 7, illustrated in Figures 8 and 12.

These dogs are pivotally secured at one end on screws 8 and are urged outward at the opposite end by springs 9.

The disc 2 is provided with a collar 11, Figures 8 and 5, on which is rotatively mounted a control plate 12, Figures 5 and 9. This plate 12 is provided with apertures 13, corresponding in number with the dogs 7, and adapted, when said plate is rotated in one direction on collar 11, to depress said dogs into recesses 6, and when oppositely rotated, to permit the rise of said dogs, under urge of springs 9.

20 The control plate 12 is provided with a finger 14 extending radially therefrom for co-action with parts to be later described.

At 16, Figures 5 and 14, I show a ratchet plate or disc provided with a central bore 17 to admit therethrough a sleeve 18, Figure 5, on a member 19. The ratchet plate 16 is secured by screws 20 to the disc 19 and both are intended to rotate with the shaft 1 because of the member 19 being keyed thereto, as shown 30 at 21, Figure 1.

At 22 I show an annular housing member adapted to form a close fit around the member 19 and, when secured to disc 2, as by screws 23, to enclose in grease the dogs 7, control plate 12 and ratchet plate 16. The housing member 22 is cut away at the top, as is also the disc 2 to form a support for a plate 24 which is secured to disc 2. The top flat portion of the housing 22 is shown in Figure 11, wherein is shown a slot 26 for permitting a limited movement of the finger 14 on control disc 12. A slot 27 communicates with slot 26 to permit the entrance and withdrawal of the housing member 22 over said finger. Secured to the plate 24, as by screws 28, Figure 4, are guide members 29 grooved at 31, to slidably engage a slide plate 32. The plate 24 is provided with a slot 33 registering with slot 26, Figure 7, through which extends the finger 14.

50 The slide plate 32 is provided with an opening 34, Figures 4, 6, 7. This opening is of a length sufficient to permit the sweep of finger 14 through the length of slot 33 and of a width, at one end, to provide a notch 36 for engaging said finger 14 when the same is in the reversing position shown in Figure 6.

At 37 I show an oblique cam surface forming a part of the boundary of the opening 34. In order to move the slide plate 32 to engage 60 finger 14 in the different positions shown in Figures 4 and 6, I provide a slot 38, in said plate, Figures 4 and 7. Extending into slot 38 is the bent end 39 of a member 41, the threaded end of which is secured to a selector rod 42 of the transmission to which my

device is attached. The purpose of slot 38 is to provide a lost motion connection whereby the member 41 may have a limited movement relative to the slide plate 32 when the selector rod is moved from a forward gear position to a neutral position on its way to a reverse gear position and vice versa.

In Figure 13, I show a means for yieldably retaining the slide plate 32 in various positions until moved again by the selector rod. The plate 24 is provided with countersunk holes 43, at intervals corresponding with forward, neutral and reverse positions, and at 44 I show a ball urged to seat in any of said holes by a spring 46 bearing at one end against said ball and at the other end against the roof of a hollow plug 47 threaded at 48 into the plate 32.

It will be seen from the structure so far described, that, when the device is assembled as shown in Figure 1, on a propeller shaft and secured to a transmission of an automobile, and the member 41 attached to a selector rod of the gear shift, each movement of the said selector rod will move in corresponding degree the member 41. Assuming that the said rod is in the forward gear position (Figure 4) the slot 38 will be in the position (relative to member 41) shown in Figure 7.

If the gear be shifted to a neutral position the member 41 will move toward the plate 32 but will impart no movement thereto the member 41 moving until the end 39 is in the opposite end of said slot 38. At this time, if another forward shift be made, the movement will be reversed without changing the position of plate 32.

However, if a reverse gear shift be made, the member 41 (coming in contact with the end of slot 38) will move said plate 32 to the position shown in Figure 6. In this position the finger 14 is engaged in notch 36 of said plate holding the control plate in a position where it retracts and holds the dogs 7 from engagement with teeth 9 of the ratchet plate 16, thus permitting a reverse movement of the car, when in response to a shift to reverse position.

If a shift be made from reverse position to neutral position the movement just described will be reversed without any movement of plate 32 because of the lost motion connection afforded by the length of slot 38 which affords a permissible limit of travel of the member 41.

It will be seen that the movement of plate 32 to reverse position (Figure 6) will throw finger 14 (should said finger be in locked position) because of the oblique cam surface 37 in contact therewith.

The member 41 is connected to that selector rod 42 which controls first speed (low) and reverse speeds.

I will now describe mechanism operable in

response to, and associated with the other selector rod 40 which controls second, and third (intermediate and high) speeds.

In Figures 7, 15 and 16 I show a pin 45 secured to slide 32 and extending upward through a slot 50 in a member 55 threaded into the end of selector rod 40. The length of slot 50 is equivalent to the limit of travel of the selector rod 40 from second to high speeds.

When selector rod 40 is moved to neutral position (indicated in dotted lines at N in Figure 15) the pin 45 will be in the center of the length of slot 50.

The purpose of pin 45 and member 55 is to provide means for moving plate 32 from the position in which it is shown in Figure 16 to the one it assumes in Figure 15 in order to release finger 14 to make the reverse lock automatically effective.

It will be seen that slide plate 32 can only get to position shown in Figure 16 in response to a reverse shift through selector rod 42 and member 41.

I will now describe means by which said plate 32 will be returned to its position in Figure 15 in response to any forward shift.

First, if selector rod 42 be moved to first speed ahead member 41 will engage in the end of slot 38 and move said plate.

A movement of the other selector rod 40 to high will also move plate 32 by reason of the pin 45 engaging the end of slot 50.

It will be seen that the selector rod 40 must be moved backward from high to intermediate or second speed. In order to cause this retractive movement to the selector rod 40, to move plate 32 in the opposite direction I provide a lever 49 fulcrumed on a screw 51 secured to base plate 24. One end of lever 49 is provided with a slot 60 through which extends a pin 52 secured to plate 32. The opposite end of lever 48 is rounded and extends into the path of travel of selector rod 40. When said rod is shifted into second it abuts said lever, causing it to oscillate on its pivot and thereby move plate 32.

The finger 14 is normally held at the left of the slot in plate 32 (Fig. 15) by frictional engagement of the control plate 12 (integral with said finger) with the ratchet disc 16. This frictional engagement is always present when the car is moving in a forward direction. If no other means were provided for controlling the movement of finger 14 the ratchet locking means would automatically free the car to move forward and lock it against a movement backward. The controls described in this application are for the purpose of rendering the locking device inoperative when it is desired to reverse and the provision of means associated with, and responsive to, conventional gear shift mechanism for doing this automatically. The only time that finger 14 is ever at the opposite (right)

side of the slot in plate 32 is when the car is locked against movement in a reverse direction. When so locked the first movement in a forward direction will return said finger 14 to its normal position.

I will now describe means manually operated, independent of gear shift mechanism, for suspending or rendering inoperative the reverse lock.

I have described means responsive to all gear shifts for rendering the reverse lock mechanism inoperative, and now will describe means for doing so under certain conditions where a shift of gears is inadvisable as, for instance, assuming that the vehicle is on an up grade and the driver desires to drop back without shifting to reverse, by releasing his clutch.

At 61 I show a slide member (shown in detail in Figure 20) which slides longitudinally in a groove 62 in base plate 24, Figure 7. This plate 61 is provided with an opening 63 corresponding in shape and length with slot 26, Figure 11, and with holes 64 and 66 for engagement with ends of springs 67 and 68 respectively. The end of spring 68 remote from slide 61 is secured to the frame 69, Figure 15, or any stationary part.

The end of spring 67 remote from slide 61 is secured to one end of lever 71, fulcrumed at 72. Lever 71 carries on its end a roller 73 which normally abuts the end of a plunger 74 slidably in a bearing 76 secured at 77 to the frame.

The plunger 74 extends through the floor board 78 and is surmounted by a pedal 79. The pedal and plunger 74 are normally held in the position shown in Figure 15 by a spring 81 bearing at one end against said pedal and at the other end against floor 78.

If pedal 79 be depressed, lever 71 will move to its dotted line position placing spring 67 under tension. When this occurs, if the dogs 7 are not in contact with teeth 9, the slide 61 will respond to the urge of spring 67 and move to the position shown in Figure 16, the slot 63 carrying finger 14 to the position shown in Figure 16.

However, should dogs 7 be in contact with teeth 9 (as when the vehicle is being held by the dogs 7 from backward movement down hill, at which time the weight of the car would cause contact between dogs 7 and teeth 9 thus preventing movement of the control plate 12, the finger 14 of which extends through slot 63) the movement of slide 61 will be delayed and spring 67 will be put under tension until such time as the dogs 7 and teeth 9 disengage. Any slight movement (forward) of the car will cause this disengagement. Thereupon the slide 61 will carry finger 14 to the position permitting backing of the car.

As the manual mechanism just described is only for a backing down movement of the

car it is obvious that a latch means should be provided to hold slide 61 against its return should the manual means (pedal 79) be inadvertently released. Therefore, I provide in slide 61 a notch 82 for engaging the edge of a member 83 on a sliding latch member 84.

The latch member 84 is slidably mounted on guide member 29 by screws 86 extending through slots 87 which afford a slight movement of said latch member relative to said screws.

The latch member 84 is normally urged to the position shown in Figure 16 by a spring 88 secured at one end to guide member 29 and at the opposite end to a pin 89 in a hole 91 of the latch member.

It will be seen that when pedal 79 is depressed, slide 61 will move until stopped by the engagement of a pin 92 with guide member 29, at which time slot 82 registers with latch member 83 which (under urge of spring 88) moves into said notch.

Latch 83 cannot be disengaged from plate 61 by any accidental release of the manual means (pedal 79) but can be released, automatically, in several ways by the movement of other parts as follows: First, in response to any forward movement of the car, as the finger 14 moves to the position shown in Figure 15, said finger encounters a cam surface 93 on latch member 84. As the surface 93 is oblique to the line of travel of said finger the finger will depress member 84 releasing latch 83 from notch 82;

Second, a shift to reverse moves selector rod 42 and the end of member 41 thereon extending into slot 38 (Figure 16) moves plate 32 which at the extreme of its movement engages a turned down lip member 94, Figure 17, of latch member 84 which when moved also disengages latch 83 from notch 82;

Third, a shift to second speed will move selector rod 40 to a point where the end of said rod will contact with the end 96 of latch member 84 and move same sufficiently to release latch 83 from notch 82.

The release of latch 83 from notch 82 by any of the means described leaves plate 61 free to return to the initial position, shown in Figure 15, under the urge of spring 68, assuming that the greater urge of spring 67 has been released by the release of pedal 79.

The operation of the device is as follows:— When the device is assembled as shown in Figure 1 and the member 41 is attached to the selector rod 42 of the gear shift for low and reverse speeds, each movement of said selector rod will move the member 41. Assuming that the said rod is in the forward gear position the slot 38 will be in a position relative to the member 41 as shown in Figure 7. If the gear shifted to a neutral position the member 41 will move toward the

plate 32 but on account of the lost motion will impart no movement thereto until the end 39 is in the opposite end of the slot 38. At this time if another forward shift should be made the position of the plate 32 will not be changed.

However, if the gear is shifted to reverse the member 41 will move the plate 32 to the position shown in Figure 6 with the finger 14 located in the notch 36 of the plate 32 thereby holding the dogs 7 from engagement with the teeth 9 of the ratchet plate 16 thus permitting a reverse movement of the car in response to a shift of the gears to reverse position.

Due to the lost motion in the slot 38 a shift being made to neutral position would have no effect upon the plate 32. It will be noticed therefore that a movement of the plate 32 due to placing the gear shift in reverse has the effect to render the reverse mechanism inoperative.

The selector rod 40 is associated with the intermediate and high gear shift and by means of the pin 45 operating in the slot 50 of the member 55 the plate 32 can be moved from the position in which it is shown in Figure 16 to that shown in Figure 15 in order to release the finger 14 and render the reverse lock mechanism automatically effective. When the selector rod 40 is moved backward from high to second speed the lever 40 fulcrummed at 41 is operated by the rounded end coming in contact with the selector rod 40. This causes the rod 49 to pivot and thereby move the plate 32 to the position shown in Figure 15.

The manual mechanism operating the slide 61 is used when it is desired that the vehicle be moved backwardly without the necessity of shifting the gears to reverse. Depressing the plunger 74 through the slide lever 61 places the finger 14 in inoperative position. Means are also provided to lock the slide 61 until a forward movement of the car takes place and cause the disengagement of the latching mechanism for the slide 61.

I claim:

1. The combination, with the power transmission and gear shift mechanism of an automobile, of a reverse lock mechanism, an automatic control means for said lock, responsive to conventional gear shift mechanism for, selectively, rendering said lock operative or inoperative, manually operated means, independent of said automatic means, for actuating said control means to render said lock inoperative, and resilient means, interposed between said control and said manual means, whereby, should strain on the transmission prevent the movement of said control immediately, said movement will take place as soon as said strain is removed.

2. The combination, with the power transmission and gear shift mechanism of an auto-

mobile, of a reverse lock mechanism, an automatic control means for said lock, responsive to conventional gear shift mechanism, for, selectively, rendering said lock operative or inoperative, manually operated means, independent of said automatic means, for actuating said control means to render said lock inoperative, resilient means interposed between said control means and said manual means, and latch means for restraining said control means when actuated in response to said manual means.

3. The combination, with the power transmission and gear shift mechanism of an automobile, of a reverse lock mechanism, an automatic control means for said lock, responsive to conventional gear shift mechanism, for, selectively, rendering said lock operative or inoperative, manually operated means, independent of said automatic means, for actuating said control means to render said lock inoperative, resilient means, interposed between said control and said manual means, latch means for restraining said control means when actuated in response to said manual means, and means, automatically responsive to any forward movement of said automobile, for releasing said latch.

4. The combination, with the power transmission and gear shift mechanism of an automobile, of a reverse lock mechanism, an automatic control means for said lock, responsive to conventional gear shift mechanism, for, selectively, rendering said lock operative or inoperative, manually operated means, independent of said automatic means, for actuating said control means to render said lock inoperative, resilient means, interposed between said control and said manual means, latch means for restraining said control means when actuated in response to said manual means, and means, automatically responsive to a shift of gears to second forward position, for releasing said latch and rendering said reverse lock operative.

5. The combination, with the power transmission and gear shift mechanism of an automobile, of a reverse lock mechanism, an automatic control for said lock, responsive to conventional gear shift mechanism, for, selectively, rendering said lock operative or inoperative, manually operated means, independent of said automatic means, for actuating said control means to render said lock inoperative, resilient means, interposed between said control and said manual means, latch means for restraining said control means when actuated in response to said manual means, and means, automatically responsive to a shift of gears to reverse position, for releasing said latch and rendering said lock operative.

6. The combination, with the power transmission and gear shift mechanism of an automobile, of a reverse lock mechanism, and

means responsive to conventional gear shift mechanism for, selectively, rendering said lock operative or inoperative, and positive means for securing said reverse lock in inoperative position when desiring to make a shift of gears to reverse position.

7. The combination, with the power transmission and gear shift mechanism of an automobile, of a reverse lock mechanism, means responsive to conventional gear shift mechanism for, selectively, rendering said lock operative or inoperative, positive means for securing said reverse lock in inoperative position when desiring to make a shift of gears to reverse position, and means for maintaining said reverse lock in inoperative position when said gears are shifted from reverse to neutral position.

8. The combination, with the power transmission and gear shift mechanism of an automobile, of a reverse lock mechanism, means responsive to conventional gear shift mechanism for, selectively, rendering said lock operative or inoperative, positive means for securing said lock in inoperative position when desiring to make a shift of gears to reverse position, and means, automatically responsive to a shift of gears to any forward speed position, for releasing said positive means and rendering operative said lock.

In testimony whereof I affix my signature.
CHARLES P. CIRAC.
